UNITED STATES PATENT OFFICE.

WILLARD B. FEATHERSTONE, OF WASHINGTON, DISTRICT OF COLUMBIA, ASSIGNEE TO
H. P. PATENTS AND PROCESSES COMPANY, INC., A CORPORATION OF NEW YORK.

PHOTOGRAPHIC FILM.

1,145,410.

Specification of Letters Patent.

Patented July 6, 1915.

Application filed August 1, 1910. Serial No. 574,954.

To all whom it may concern:

Be it known that I, WILLARD B. FEATHERSTONE, a citizen of the United States, residing at Washington, in the District of Columbia, have invented certain new and useful Improvements in Photographic Films, of which the following is a specification.

My invention relates to the recording and projection of photographs in natural colors, and has for its object to provide a simple, convenient and inexpensive means to filter all but certain desired colors from incident rays of light. I accomplish this by the use of a colored backing or support for the emulsion, such as the transparent celluloid commonly used in the manufacture of photographic films, the photographs being taken and projected through the colored support.

In the accompanying drawings:—Figure 1 shows a three colored backing or support, partly covered with emulsion. Fig. 2 shows a strip of film whose translucent backing for the emulsion is of two different colors. Fig. 3 shows the support colored on its surface instead of throughout its mass. Fig. 4 shows a double-row strip with three colors alternating in each row.

The letters, R, G and B, in the several figures indicate the colors, red, green and blue-violet respectively, as pertaining to the color values of the potential images, which are bounded by the dotted lines in the several figures.

The vari-colored strips are useful in taking photographs, as well as in projecting them. In the former process the colored support is toward the lens, and in the latter it will ordinarily be away from the objective lens, but may be either way.

In practice there are several ways of coloring the transparent support for the photographic emulsion, but I prefer one of the following.

The celluloid or other substance is made up colored and pressed into cakes which are joined and amalgamated substantially on the lines shown in the several drawings, after which the vari-colored mass is sheeted off in layers, which will, of course, have the colors similarly distributed.

Another method is to take ordinary clear

celluloid, and, after removing the gloss, print the colors on, either in a press or by a continuous process, such as drawing the long strips through spongy pads suitably impregnated with dyes.

I am aware that colored celluloid has been used for color filters, but I am not aware and do not believe that the transparent body upon which the emulsion is mounted has ever been stained or dyed as above described for the purpose of doing away with separate filters.

In the claims the words "image" and "picture-factor" are used to designate that monochromatic portion of a full image which is transmissible by a single colored section of the support, to be impressed upon the emulsion. The word "potential" is used as designating the images or partial images which will form just beyond the color-filtering areas when the film is used in a camera, and which will cause, upon development, monochromatic negatives or picture factors.

A "primary color" is held to be any color which, when projected with one or more other colors by suitable means and in proper combinations, will reproduce substantially the natural colorings of ordinary objects. "Monochromatic" is also used approximately to denote the separate color values of the negative factors, which when made positive by printing, and combined by projection or otherwise, will reproduce the original colors of the object photographed.

The word "translucent" is used in its broad sense, as applying to all such physical conditions as permit light to shine through, including so-called transparent substances as well as those which are not entirely transparent.

The scope of this invention is not limited to the exact styles of films shown and described, its principal object being to provide a color-filtering support for light-sensitive emulsion, particularly doing away with separate filters for making monochromatic negatives, or combinable parts of color pictures.

I claim:—

1. A photographic film comprising a translucent strip having a series of exposure field sections, adjacent ones of which differ

- from each other in color, said strip having a photographically sensitive coating upon one of its surfaces.
2. A photographic film comprising a translucent strip having a series of exposure field sections, adjacent ones of which differ from each other in color, the colors of said sections substantially corresponding to the primary color sensations, said strip having a photographically sensitive coating upon one of its surfaces.
3. A photographic film comprising a translucent strip having a series of exposure field sections, adjacent ones of which differ from each other in color, arranged in regularly recurring order longitudinally thereof, said strip having a photographically sensitive coating upon one of its surfaces.
4. A photographic film comprising a translucent strip having a series of exposure field sections, adjacent ones of which differ from each other in color, arranged in regularly recurring order longitudinally thereof, the colors of said sections substantially corresponding to the primary color sensations, said strip having a photographically sensitive coating upon one of its surfaces.
5. A photographic film comprising a translucent strip having a plurality of laterally arranged longitudinal series of exposure field sections, longitudinally adjacent ones of which differ from each other in color, said strip having a photographically sensitive coating upon one of its surfaces.
6. A photographic film comprising a translucent strip having a plurality of laterally arranged longitudinal series of exposure field sections, longitudinally adjacent ones of which differ from each other in color, the colors of said sections substantially corresponding to the primary color sensations, said strip having a photographically sensitive coating upon one of its surfaces.
7. A photographic film comprising a translucent strip having a plurality of laterally arranged longitudinal series of exposure field sections, longitudinally adjacent ones of which differ from each other in color, the colors regularly recurring longitudinally, said strip having a photographically sensitive coating upon one of its surfaces.
8. A photographic film comprising a translucent strip having a plurality of laterally arranged longitudinal series of exposure field sections, longitudinally adjacent ones of which differ from each other in color, the colors of said sections substantially corresponding to the primary color sensations and regularly recurring longitudinally, said strip having a photographically sensitive coating upon one of its surfaces.
9. A photographic film comprising a translucent strip having a series of consecutive exposure field sections, successive ones of which differ from each other in color, said strip having a photographically sensitive coating upon one of its surfaces.
10. A photographic film comprising a translucent strip having a series of consecutive exposure field sections, successive ones of which differ from each other in color, the colors of said sections substantially corresponding to the primary color sensations, said strip having a photographically sensitive coating upon one of its surfaces.

WILLARD B. FEATHERSTONE.
